BEAD DIPPING APPARATUS

Nathan Hamburg, Brooklyn, N. Y., assignor to
 Joseph H. Meyer Brothers, Brooklyn, N. Y., a
 corporation of New York

Application August 4, 1945, Serial No. 608,963

5 Claims. (Cl. 91—60)

1

My invention relates to a novel device for supporting pins on which are mounted articles to be treated, and more particularly my invention relates to a device for supporting in vertical position toothpicks on which are mounted spheres which are to be treated as by dipping in plastic solutions.

In the manufacture of artificial pearls and other elements of costume jewelry which are formed by coating glass or plastic spheres, such dipping operation is best handled by supporting the sphere by a toothpick inserted in the bead hole and then supporting the toothpick vertically for a mass dipping operation.

Many difficulties arise in this supporting operation, however, because of the variance in the thickness of the toothpicks or similar supporting pin elements so that a uniform fixed hole cannot accommodate the different thicknesses of toothpicks without distortion or destruction of the hole element.

Also, it is desirable in this operation that the spheres be leveled off so that all the spheres are in the same plane for the dipping operation and the pressure exerted on the sphere and transmitted to the toothpick often causes breakages on the toothpick so that sections of broken toothpicks are left in the supporting holes.

When these holes are in metal, wood or other rigid material they become clogged up or broken so that fewer and fewer become available and the operation soon is impaired by the scarcity of available supporting holes.

It has been thought necessary, however, to use rigid openings since considerable strength is necessary for supporting the toothpicks both during the leveling off and during the dipping operations.

It is the object of the present invention to provide a novel supporting structure for holding a multiplicity of toothpicks onto which are mounted objects to be treated.

It is a further object of the present invention to provide a novel supporting device for supporting a large number of spaced toothpicks of non-uniform thickness so that the toothpicks can be vertically moved with respect to one another and so that the supporting openings can accommodate the various thicknesses of the toothpicks.

It is a further object of the present invention to provide a novel device by means of which the various toothpick supporting elements can be interchanged when their usefulness has ended

2

without expense or expenditure of any considerable time or labor.

It is a further object of the present invention to provide a novel inexpensive device for supporting and uniformly spacing a large number of toothpicks of non-uniform thickness on which are mounted spheres that are to be dipped downwardly into a plastic solution.

These objects are accomplished by providing a frame in which are set a plurality of corrugated layers, the ends of the corrugated layers being exposed to provide a number of receptive openings for supporting the toothpicks, the respective toothpick supporting rows being spaced by intermediate cushioning layers which provide a resilience necessary for the proper support and reception of the toothpicks of non-uniform thickness. By non-uniform thickness I mean that the toothpicks normally available in commerce, not only have a changing diameter running from a point at one end to a relatively thick middle portion, but the great majority of toothpicks vary as much as fifty per cent (50%) in thickness in any given portion of the toothpick. That is, the middle or area of greatest thickness in one toothpick can vary from 10-50% with respect to another toothpick from the same lot.

Since it is not economically feasible to obtain perfectly uniform diameter toothpicks for this operation because of the large number of toothpicks needed and because of the wear, tear, loss and breakage of the toothpicks, it is necessary to use such non-uniform diameter commercial toothpicks.

In the drawings, Figure 1 is a perspective, partially cut away, showing the device of my invention.

Figure 2 is an enlarged small portion of the device of my invention showing the open ended corrugated toothpick supporting elements with the intermediate cushioning layers therebetween partially cut away to show their construction.

Figure 3 is a top view, partially cut away, showing the toothpicks in spaced relation in the corrugations in the device of my invention.

Referring now more specifically to the drawings, in Figure 1 I show a supporting frame generally referred to as 10 which comprises side pieces 11 and 12 and end pieces 13 and 14. The end pieces and the side pieces are suitably joined as by screws 16. For convenience in handling the frame 10 handles 17 and 18 are affixed to end pieces 14 and 13 respectively.

The side pieces 11 and 12 are slotted on their inner faces as shown so as to receive the tooth-

3

pick supporting elements more clearly shown in Figure 2. Like reference numbers will be used for like elements in Figures 1, 2, and 3.

The toothpick supporting elements as shown in the figures specifically comprise a central rigid supporting element 20 which may be of wood, plastic or metal and positioned at each side of said rigid element 20 are corrugated layers generally referred to as 21 and 21'. Corrugated layer 21 comprises a corrugation 22 with liners 23 and 24 affixed to each side of said corrugation as by adhesives which secure the contacting portion of the corrugation 22 to that portion of the liners 23 and 24 which it is in contact with.

Both the corrugation 22 and the liners 23 and 24 may comprise paper, cardboard or paper or cardboard impregnated with a stiffening agent such as resin or cellulose plastic.

Alternatively the corrugated material can be formed from a resin or plastic or a mixture of resins or plastics. Suitable plastics are, for example, cellulosic plastics such as the cellulose esters, cellulose nitrate, cellulose acetate, cellulose aceto propionate and cellulose aceto butyrate or the cellulose ethers such as ethyl and benzyl cellulose.

The resins that may be employed here for the impregnation of paper or cardboard corrugated elements, or which may be used per se as the corrugated or liner elements are the vinyl compounds, such as the conjoint polymer of vinyl chloride and vinyl acetate or the vinyl acetal resins such as vinyl butyral, linear polyamides such as those sold under the trade name of "nylon" and the various other resins possessing flexibility and sufficient strength to perform the function of a corrugated element as described herein.

I have particularly found it desirable to use resin impregnated corrugated elements for reasons that will be set out more specifically hereinafter.

The toothpick supporting element therefore comprises an open end corrugated layer positioned and supported by an adjacent rigid piece.

The corrugated layers have their open ends exposed to receive the toothpicks as shown in Figures 2 and 3. It is necessary, however, to provide considerable resilience in these corrugated layers in order to firmly hold the toothpicks, to accommodate toothpicks of various thickness and to properly support said toothpicks when and if such toothpicks are moved vertically with respect to said corrugated toothpick supporting elements.

This resilience and gripping force is obtained by interspacing said toothpick supporting elements with resilient members which comprise a double corrugation consisting of a corrugated member 26 and a corrugated member 27 affixed to one another by liner 28 and externally covered with sheets 29 and 30. This double corrugated element is preferably covered over with cover 32 which may, for example, comprise an ordinary sheet wrapping of paper or plastic sheet material which completely surrounds the double corrugation and its covering and joining elements 28, 29 and 30, or the cover element 32 may merely cover the exposed end corrugations.

It is desirable that the corrugations be as completely closed as possible since I have found that by so doing I obtain a resilience, improved over the resilience formed by the corrugated structure itself. That is by closely covering the cor-

4

rugated cells or by completely sealing the corrugated cells I obtain a cushioning element that comprises a multiplicity of sealed air cells.

When the toothpicks 34 on which are mounted the glass or plastic spheres 35 are pressed into the open end corrugations as shown, they bear against the resilient corrugation cushion which comprises the corrugated elements 26 and 27 bound together and sometimes hermetically sealed by the cover 32. This corrugated cushion element is generally referred to as 37 and as shown in Figure 1 and Figure 2, it interspaces the toothpick supporting elements 21 which are set into slots 38 and 39 of the side elements 11 and 12. To hold these elements in place I provide a bottom supporting member 40 fixed or formed integrally with the side member 11 and a similar bottom supporting element 41 which is affixed to the side element 12.

20 To hold the toothpick supporting elements 21 and the cushioning elements 37 in place when the board is handled or reversed in the course of operation, I provide securing strips 42 and 43 which are suitably affixed to the side members 11 and 12 by screws or bolts 45.

The device of my invention is assembled by removing the securing strips 42 and 43 from the side members 11 and 12 and inserting in the slots 38 and 39 the toothpick supporting elements 21 which comprise the central rigid member with two corrugated layers affixed thereto.

35 Positioned between these toothpick supporting elements and in pressure contact therewith are the corrugated elements generally referred to as 37 and which comprises a covered assembly of at least one corrugated element to provide increased resilience and gripping strength to the corrugated elements 22 into whose exposed ends are inserted the toothpicks 34.

40 When the entire tray is filled with the toothpick supporting elements 21 and the interspaced cushioning elements 37, the securing strips 42 and 43 are secured as shown in Figures 1 and 3 over the side members 11 and 12 to hold these 45 toothpick supporting elements and cushioning elements in place.

When toothpicks are inserted into these corrugations they are firmly held in the desired vertical position and when the spheres 35 are 50 pressed down into alignment with one another, the toothpicks are held in their end position firmly and surely throughout the treating operation.

Because of the great number of openings provided, the same board can be used for all sizes of beads, since spacing of the toothpicks is determined by the size of the bead.

There is little damage normally done to the corrugations by insertion of the toothpicks or by 60 pressing of the spheres on the toothpicks, but when damage does occur either through mis-handling or through extended wear, the great numbers of receptive openings available makes replacement necessary over only extended periods 65 since there are usually sufficient operative receptive openings in the corrugations 22 fixed to the liners 23 and 24 available for a considerable period of time.

In the event, however, that replacement finally 70 becomes necessary it is a relatively simple matter to remove the securing strips 42 and 43 and merely pick out damaged toothpick supporting elements which it has become necessary to replace and insert a new toothpick supporting unit 75 such as 21 or 21'. Such replacement does not

necessitate the disassembling of the entire unit and requires only that the particular damaged unit be picked out and the replacement inserted in lieu thereof.

Although I prefer not to attach the corrugated tooth pick supporting element 21 and 21' to the rigid member 20, they could be so affixed as by adhesive if desired.

The intervening cushion 32 does not extend out as far as the toothpick supporting corrugations as can be seen in Figure 3.

The rigid element 20 maintains the proper positioning of the toothpicks since it positions the corrugated layers. The rigid elements 20 also serve to line up the toothpicks since because of their rigidity they are not thrown out of line during any processing operation.

It has been found desirable to employ a plastic coated or plastic impregnated corrugated element or corrugated elements formed entirely from plastic material since plastic or resinous material is such as to provide a firm and sure grip on the toothpick while at the same time providing a surface capable of withstanding a solvent or chemical attack during the process.

The plastic or resinous material makes the corrugation substantially impervious to moisture and preferably I employ plastic or resinous material that is impervious to the solvents or chemicals used in the solutions with which the spheres 35 are treated.

Thus the flexibility and gripping strength of the corrugations are unimpaired by water or solvent absorption even over extended periods of time.

Further the surface strength of the plastic (which includes both cellulosic plastics and resins) is such as to prevent internal tearing of the corrugations by the pointed end of the toothpick since the wooden toothpick has insufficient strength to penetrate plastic or plastic coated corrugated elements.

I have also found that these corrugations when mounted on a rigid central piece and cushioned as here shown can accommodate and properly hold toothpicks of extreme differentials in diameter without permanent impairment or destruction of the corrugated element. That is, the corrugated element is made sufficiently elastic and this can of course be enhanced by the use of plastic coatings or materials so that the insertion of toothpicks having a diameter even larger than the opening of the corrugation will not permanently damage the opening or render it inoperative for later use.

The bottom of the board (not shown in the drawings) is the same as the top side shown. Thus, I can use both sides of this device and get extended life and utility therefrom.

Although I have found it desirable to employ plastic or plastic coated corrugated tooth pick supporting elements, it is to be understood that I obtain extremely satisfactory results by employing ordinary paper or cardboard corrugated toothpick supporting elements.

It will be apparent to those skilled in the art that the novel principles of the invention disclosed herein in connection with the specific exemplifications thereof will suggest various other modifications and applications of the same. It is accordingly desired that in construing the breadth of the appended claims they shall not be limited to the specific exemplifications of the invention described herein.

I claim:

1. In a device for vertically supporting tooth

pick like elements, a corrugated member comprising a central corrugated element and at least one liner element secured thereto, said corrugated element and said liner together forming a plurality of adjacent pockets adapted to receive and position toothpick elements, said corrugated member being supported to a rigid member, means for applying resilient pressure to said corrugated member, said means comprising a second corrugated member positioned adjacent to and in pressure contact with said first corrugated member, said second corrugated member having the open ends of the air cells formed within it closed by sheet material extending over said openings to increase the resilience and cushioning effect of said second corrugated member.

2. A device for vertically supporting and aligning tooth pick like elements comprising a frame, said frame having two side members and two end members, said side members having slots facing inwardly and toward the slots on the opposing side member, a plurality of elongated board like members, the ends of said elongated members fitting into and being supported in the slots in said side members, said elongated members comprising

an elongated rigid member and a substantially coextensive corrugated member comprising corrugated flexible sheet material adhesively secured at spaced contacting points to a liner positioned on each side of said elongated member, and substantially coextensive therewith, said corrugated member having an exposed end surface adapted to receive and position tooth pick elements, cushioning members positioned between said elongated members the slots in said frame being so spaced as to cause the cushioning members to press the corrugated members toward the adjacent rigid members.

3. A device for vertically supporting and aligning toothpick-like elements comprising a frame, a plurality of elongated members contained in said frame, said elongated members including an elongated rigid member and a substantially coextensive corrugated member which comprises a corrugated flexible sheet material secured at spaced contacting points to a liner positioned on at least one side thereof, said corrugated sheet and said liner together forming a plurality of adjacent pockets adapted to receive and position toothpick elements, and a resilient cushioning member in lateral pressure contact and substantially coextensive with said corrugated member to press the said corrugated member toward the rigid member.

4. In a device for vertically supporting toothpick-like elements, a corrugated member comprising a central corrugated element and at least one liner element secured thereto, said corrugated element and said liner together forming a plurality of adjacent pockets adapted to receive and position toothpick elements, said corrugated member being supported by a rigid member, means for applying resilient pressure to said corrugated member, said means comprising a second corrugated member positioned adjacent to and in pressure contact with said first corrugated member, said second corrugated member having air cells within it to increase the resilience and cushioning effect of said second corrugated member.

5. A device for vertically supporting and aligning toothpick-like elements comprising a frame, a plurality of pairs of parallel elongated corrugated members contained in said frame, each of said corrugated members comprising a corru-

gated flexible sheet material secured at spaced points to a liner positioned on at least one side thereof so that said corrugated sheet and said liner together form a plurality of adjacent pockets adapted to receive and position toothpick elements, rigid members between the adjacent surfaces of each pair of corrugated members, and resilient cushioning members separating the adjacent pairs of corrugated members, said rigid members and said resilient cushioning members being held in lateral pressure contact with the corrugated members adjacent thereto.
